UNITED STATES PATENT OFFICE

2,434,161

ELECTRICAL CONTROL FOR MULTIPLE
HEATING UNITS IN TUBES

John H. Homrighous, Oak Park, Ill.

Application August 22, 1942, Serial No. 455,747

11 Claims. (Cl. 250—27.5)

1

This invention relates in general to improvements in electronic tubes, and more particularly to tubes having a plurality of heating units.

One of the main objects of this invention is to provide means for prolonging the useful life of electronic tubes.

Another object of this invention is the provision of switching mechanism inside the evacuated envelope for automatically changing the filament or the heating units when one is burned out.

Another object of my invention is the provision of means whereby if a heating unit in a vacuum tube be operating at low efficiency it may be replaced by another heating unit.

Still another object of this invention is the provision of means for visibly signalling an attendant when the heating unit in an operating vacuum tube is burned out.

Various types of radio tubes have been devised having several heating units that may be separately energized through switching mechanism in an attached accessory. In my invention I provide an evacuated tube or bulb, having multiple heating units with switching mechanism supported in the tube for utilizing the different heating units, the mechanism being held under tension or released through the action of a bimetallic spring automatically or manually controlled.

These and other objects and advantages will be apparent from the following detailed description, reference being had to the accompanying drawings in which:

Figure 1 is a plan view partially in section of a radio tube with heating unit switching mechanism.

Figure 2 is a top detail view of mechanism taken on lines 2—2 in Figure 1.

Figure 3 is a detail view of mechanism taken on line 3—3 in Figure 1.

Figure 4 is a schematic of the circuit.

In the drawing the reference numeral 1 represents a radio tube broken away to show the filament or heating unit switching mechanism on the inside of the evacuated bulb. In the center of this bulb is a hollow stem 4 extending upward from the base and having two ceramic disks 5 and 6 rotatably mounted near the top of the stem 4. These disks are fastened together by the stabilizing bar 7, Figure 2, so that they will rotate together. The disks are limited in their travel by the pin 8 engaging the elongated slot in the lower rim of the disk 5. The disks 5 and 6, under tension of the spring 9 which is

2

secured to the disk 6 and to the plate 10, are held in the position shown in Figure 1 by the bimetal stop member 11 engaging the pin 12 in the disk 5. The disk 6 is provided with two pins 13 and 14 which are connected to the heating units 15 and 16 respectively. The other terminals 15' and 16' of the heating units are connected near the top of the supporting stem 4 to a single conductor extending through the stem 4 to a prong 10 in the base of the tube. The heating units 15 and 16 may be placed inside of the indirectly heated cathodes 17 and 18. The bimetal flexing device 11 is secured to ceramic plate 10 near the base of the tube and is provided with a coil 19. The conductors to the coil may extend through the stem 4 to prongs in the base of the tube or they may be sealed through the side of the tube. Current flowing through the coil produces heat which will flex the bimetal member 11 outward to disengage the pin 12, whereby the disks 5 and 6 will rotate through the action of spring 9.

The brush or wiper 20 is secured to the plate 10 and normally engages the pin or contact 13. A conductor may extend from the brush 20 through the stem 4 to a prong in the base of tube.

With reference to Figure 4 showing the circuit arrangement that may be employed with the radio tube, the relay 21 is connected in series with the radio tube filament and upon deenergizing responsive to a broken filament will cause the lamp 22 to glow.

The operation of the switching mechanism shown in Figures 1, 2 and 3 is as follows, reference being to Figure 4. A source of current supply not shown is supplied over conductors 27 to the heating unit 15, through the relay 21, contact 13 and brush 20. The relay 21 will now be energized holding contacts 23 and 24 open. However, should the unit 15 become broken or burn out, the relay 21 would release its armature to close a circuit through the lamp 22 at contacts 23, thereby giving a visible signal to indicate that a filament has been broken. The release of relay 21 will also close a current supply circuit at contacts 24 through the heating coil 19 and switch contacts 25, whereupon the bimetal stop member 11 will be fixed automatically to disengage the pin 12, allowing the disks 5 and 6 to be rotated through the action of coil spring 14 so that the brush 20 will contact the pin 14 placing the heating unit or filament 16 across the current supply circuit.

The switch 25 may be left open. The attendant, upon receiving the signal at 22, may operate 55 the key 26 to effect a change in the heating unit.

The attendant may operate the key 26 at any time to replace a low efficiency filament with a second filament.

The embodiments of the invention which have been given herein are illustrations of how the various features may be accomplished and of the principles involved. It is to be understood that the invention contained herein is capable of embodiment in many other forms and adaptations, without departing from the spirit of the invention and the scope of the appended claims.

Having thus described my invention I claim:

1. A radio tube having a plurality of filaments one end of each filament electrically connected to one terminal of said tube, a brush electrically connected to another terminal of said tube to engage individual contacts on the opposite end of each of said filaments, a spring controlled rotatable device for causing said contacts to successively engage said brush, a flexible stop member holding said device under tension of said spring to maintain said brush in engagement with one of said filament contacts and means for flexing said stop member to release the said device thereby rotating another one of said filament contacts into engagement with said brush.

2. An evacuated radio tube having a plurality of filaments, a source of current, a spring controlled rotatable switch mechanism connecting said filaments in succession to the source of current, a movable holding device maintaining said mechanism under tension of said spring to connect one of said filaments to the source of current, an electrical release coil for said holding device, and means including said coil for moving said device to rotate the said switch mechanism whereby another one of said filaments is connected to the source of current.

3. An evacuated radio tube having a plurality of filaments each provided with a contact, a brush, rotatable mechanism under spring tension for connecting said brush to said contacts in succession, a movable holding device for said mechanism to maintain said brush in engagement with one of said contacts, and means for moving said device to release said mechanism whereby the said brush engages another one of said contacts.

4. An evacuated tube having a pair of filaments each provided with a contact, a brush, rotatable mechanism under spring tension for moving said contacts to engage said brush, a movable holding device for said mechanism to maintain said brush in engagement with one of said contacts, and means for automatically moving said device to rotate said mechanism, whereby another one of said contacts is moved into engagement with said brush.

5. An evacuated radio envelope having a pair of cathode heater filaments each provided with a terminating contact, a brush, switching mechanism in said envelope under spring tension connecting said brush to said contacts in succession, a bi-metallic holding device for said mechanism to maintain the said brush in engagement with one of said contacts, and means for flexing said device to release said mechanism, whereby the said brush engages another one of said contacts.

6. In an evacuated radio envelope, switching mechanism comprising a disk rotatably supported in said envelope under spring tension provided with a pair of contacts extending from the rim of the disk, a member mechanically connected to

said disk provided with a slot, a stationary pin engaging in said slot to limit the rotation of said mechanism, a brush for engaging said contacts in succession, a bi-metallic stop member for holding said mechanism under tension of said spring to maintain said brush in engagement with one of said contacts, a resistance coil for said member, means including said coil for flexing said member out of its holding position thereby rotating said mechanism to connect said brush with another one of said contacts.

7. An evacuated radio tube having a pair of filaments each provided with a terminating contact, a brush, a spring actuated switching mechanism supported in said envelope connecting said brush to said contacts in succession, a bi-metallic stop member holding said mechanism under tension of said spring to maintain said brush in engagement with one of said contacts, a signal device associated with said tube to inform an operator that one of said filaments has been broken, and electrical operable means to actuate said signal device and to cause the said stop member to flex out of its holding position to release said mechanism, whereby the said brush engages another one of said contacts.

8. An evacuated radio envelope, a snap switch mechanism comprising a disk pivotally supported under spring tension in said envelope provided with a pair of contacts extending from the rim of the disk, a member mechanically connected to said disk, a stationary pin adapted to engage said member to limit the rotation of said mechanism, a brush engaging said contacts in succession, a movable stop member holding said mechanism under tension of said spring to maintain said brush in engagement with one of said contacts, and means for moving said stop member out of its holding position to cause a snap movement of said mechanism to connect another one of said contacts with said brush.

9. In an article of manufacture, a pair of electrical elements each provided with a terminal contact, a spring brush adapted to engage said contacts in succession, a snap switch mechanism comprising a disk pivotally mounted under spring tension connecting the said brush with a first one of said contacts, a member mechanically connected to said disk, a stationary pin adapted to engage said member to limit rotation of said mechanism, a bi-metallic stop member holding said mechanism under tension of said spring to maintain said brush in engagement with a second one of said contacts, and means for flexing said stop member out of its holding position to cause a snap movement of said mechanism to connect said brush with said first contact.

10. An electrical load element provided with a terminal contact, a source of current supply, a spring brush engaging said contact, said load element, said contact and said brush being connected in series to said source of current supply, a spring actuated mechanism adapted to separate the said brush from said contact, a bi-metallic stop member holding said mechanism under tension of said spring, and means for flexing said stop member out of its holding position to release said mechanism thereby disengaging said brush and said contact to disrupt current flow through said load element.

11. A radio tube having a plurality of filaments having one end of each filament electrically connected to one terminal of said tube, a brush electrically connected to another terminal

nal of said tube and engaging individual contacts on the opposite end of each of said filaments, a spring controlled rotatable device for causing said contacts to successively engage said brush, a flexible stop member holding said device under tension of said spring to maintain said brush in engagement with one of said contacts, a signal member adjacent said tube for informing an operator that one of said filaments has been disrupted, means for actuating said signal member following the disruption of one of said filaments, and means for flexing the said stop member out of its holding position to release said device to thereby rotate another one of said filament contacts into engagement with said brush.
